UNITED STATES PATENT OFFICE.

THOMAS I. RANKIN, OF PHILADELPHIA, PENNSYLVANIA, ASSIGNOR TO
ABRAM COX STOVE COMPANY, OF PHILADELPHIA, PENNSYLVANIA,
A CORPORATION OF PENNSYLVANIA.

DESIGN FOR A PORTABLE RANGE.

SPECIFICATION forming part of Design No. 35,455, dated December 17, 1901.

Application filed August 16, 1901. Serial No. 72,318. Term of patent 7 years.

To all whom it may concern:

Be it known that I, THOMAS I. RANKIN, a citizen of the United States, residing in Philadelphia, Pennsylvania, have invented and produced a certain new and original Design for a Portable Range, of which the following is a specification.

My design for a portable range is clearly illustrated in the accompanying drawing, which represents the range in perspective.

The essential feature of the design is the ornamentation of the base, the doors, and the hot-water chamber of the range.

E is the base of the range, having legs *e* and an apron *e'*. In the center of the apron is a medallion, and extending from the medallion toward the legs are foliated scrolls. On the upper part of each leg, in line with the apron, is a leaf-scroll, and below the leaf-scroll are two spiral scrolls.

In the center of the oven-door *E'* is an oval medallion *e²*, raised and ornamented in keeping with the design of the range, and in the two lower corners of the door are small foli-

ated scrolls, and in the upper corners and above the medallion are ornamental leaf-scrolls. The balance of the door is plain.

The fire-door *E²* has a single design, having a central oval medallion, on each side of which is a shell-scroll terminating in a small foliated scroll.

The design of the hot-water chamber *E³* is in keeping with the design on the body of the stove, and in the center of the chamber is a medallion surrounded by scroll ornamentation.

I claim—

The design for a portable range as herein described and as illustrated in the accompanying drawing.

In testimony wherof I have signed my name to this specification in the presence of two subscribing witnesses.

THOMAS I. RANKIN.
